UNITED STATES PATENT OFFICE.

OSCAR W. RICHARDSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TRANSFER CONTROLLER FOR WEFT-REPLENISHING LOOMS.

Application filed November 24, 1923. Serial No. 676,822.

To all whom it may concern:

Be it known that I, OSCAR W. RICHARDSON, a citizen of the United States, residing at Worcester, in the county of Worcester and State of Massachusetts, have invented a new and useful Transfer Controller for Weft-Replenishing Looms, of which the following is a specification.

This invention relates to weft replenishing looms and more particularly to the control for the transfer mechanism by means of which a fresh bobbin is inserted in the active shuttle.

In the type of loom illustrated in United States patent to Ryon No. 933,492, the replenishing mechanism comprises a transfer arm to the lower end of which is pivotally connected a transfer latch. When a change is indicated the latch is raised into the path 10 of a bunter on the lay by means of connections from the top shaft of the weft replenishing mechanism. The connector between the top shaft and the latch is similar to that shown in Patent No. 1,022,108; the lower end 20 of the connector being guided by a stud fixed to some stationary part of the loom above the transfer latch. The connector and its cooperative stud are so designed that the former has a vertical movement and is 30 as near the shuttle box in its lower as in its upper position.

Through an occasional faulty operation of the magazine, the bobbin which should be transferred becomes misplaced and lies between the lay and the aforesaid connector. The connector is so close to the lay that under such conditions either the bobbin or some part of the replenishing mechanism is likely to be broken.

40 The latch is generally below its pivotal connection with the transfer arm and as the latter assumes normal position after transfer the latch moves downwardly and also forwardly. The latch controller at this 45 time has a downward motion only and does not have a corresponding forward motion to move it to a safer position.

With a view to overcoming these objections I have provided means whereby the 50 guide for the controller is located below the latch and in such a position that it is not likely to be struck by the bobbin and I have

further provided for giving the lower end of the controller a forward as well as downward motion as it assumes normal inoperative position. 55

A further object of the invention is to provide a slotted latch through which the controller passes, the latter being thus guided and restrained against lateral motion. 60

A still further object of the invention is to provide the latch and its controller with interengaging members so arranged that the weight of the latch when the latter is in inoperative position serves to hold the controller in its foremost position. 65

With these and other objects in view, which will appear as the description proceeds, my invention resides in the combination and arrangement of parts hereinafter described and set forth in the claims. 70

In the accompanying drawings, wherein one form of my invention is shown,

Fig. 1 is a vertical transverse section of a weft replenishing mechanism having my invention applied thereto, 75

Fig. 2 is a front elevation of a portion of the mechanism showing the parts illustrated in Fig. 1,

Figs. 3 and 4 are detailed views showing 80 the parts in different positions, and

Fig. 5 is a horizontal section taken on line 5-5 of Fig. 4 and showing the slotted latch and controller.

Referring to Figs. 1 and 2, I have shown 85 a portion of the loom side 10 having mounted thereon replenishing mechanism 11 including a transfer arm 12, pivotally connected thereto by means of stud 13. Depending from the transfer 12 are arms 14 to 90 which is pivotally connected as at 15, the latch holder 16. The top shaft 17 of the replenishing mechanism has fastened thereto an arm 18 having a forward extension 19 passing into the slot 20 formed in one arm 95 of a lever 21, pivoted to the replenishing mechanism at 22. A spring 23 serves to hold the parts in the position shown in Fig. 2, set screw 24 carried by the lever 21 engaging a part of the replenishing mechanism to limit movement of the parts. A latch 25 is bolted to the holder 16 and is in operative relation with the lower end of a latch controller 26, the upper end of which

100

is pivoted to the lever 21 as at 27. When weft replenishment is to occur, shaft 17 is turned in a clockwise direction as viewed in Fig. 2, connector 26 is raised and the latch 25 is moved to the dotted line position shown in Fig. 1. As the lay advances, the bunter 28 formed thereon engages the latch to depress the transfer 12.

The mechanism thus far described and 10 its operation are substantially the same as shown in the previously mentioned Patent No. 933,492 to which reference may be had for a more complete description of the same.

My invention is directed to the latch and 15 the controller cooperating therewith. It will be seen by referring to Fig. 5 that the latch is formed with a slot 30 through which passes the head 31 adjustably connected to the lower end of the controller rod 26. At a 20 point below the latch 25 the head is provided with oppositely extending fingers 32 which are so placed as to lift the latch when the controller is raised. Extending from the head 31 is a cam projection 33 having a 25 steep and substantially vertical cam portion 34 near the end thereof and a shallower cam portion 35 located between the face 34 and the fingers 32. A fixed guide block 36 has a bolt and slot connection with some stationary part of the loom by means of which 30 it may be adjusted.

In operation the parts normally assume the full line position shown in Fig. 1, but when transfer is called for the parts move 35 as previously described to raise the latch to the dotted line position, this raising of the latch being effected by means of fingers 32 engaging the under side of latch 25. As the lay advances, the bunter 28 engages the 40 latch 25 and moves the latter forwardly, the latch controller being in the position shown in Fig. 3 with the steep cam face 34 in contact with the guide 36. As the lay advances the curved under face 37 of the latch engages the fingers 32 to depress the controller and the substantially vertical face 34 cooperates with the block 36 to effect a rapid 45 lowering of the controller.

The knuckle joint connectors shown in 50 Fig. 2 and the upper end of face 34 are so arranged that as the face 34 is about to leave guide 36 the spring 23 will act to lower the controller and move the latter to the position shown in Fig. 4. The cam face 35 55 is much shallower than the face 34 and as the controller descends, it is permitted to move forwardly toward the guide 36 by reason of the fact that the pivotal connection 27 between the controller 26 and the lever 21 is forward of the head 31 when the latter 60 is in its foremost position.

When the lay moves back and bunter 28 65 releases latch 25, the latter falls to the position shown in Fig. 1, the fingers 32 being engaged by the faces 37 to force the head 31

forwardly under the weight of the controller. It will be noted from an inspection of Figs. 1 and 3 that the front end of slot 30 in the latch is farther forward when the latch is down as in Fig. 1 (full lines) than it is when raised as in Fig. 3, thus permitting the controller head 31 which passes through the latch to remain in forward position when the latch is restored to normal position from the position shown in Fig. 4. 70 Also it will be seen that the controller moves to its foremost position on the transferring pick because of the fact that the latch has been moved forwardly at that time.

From the foregoing it will be seen that I 80 have provided a fixed guide below the latch for cooperating with the latch controller, that the controller has a combined forward and downward movement, that the latch is slotted to receive the latch controller so that 85 the latter is restrained against undesirable lateral motion, and that when the latch is in lower inoperative position it serves to hold the controller in forward position.

Having described one form of my invention, it will be apparent that changes and 90 modifications may be made therein by those skilled in the art and I do not wish to be limited to the specific structure illustrated, but what I do claim is:

1. In a weft replenishing mechanism for a loom having a lay, a transfer, a latch pivotally connected thereto, a controller for said latch normally in forward position away from the lay, and means to give said controller an upward and rearward movement prior to transfer to raise the latch and a downward and forward movement during transfer to restore said controller to forward position away from the lay. 105

2. In a weft replenishing loom, a transfer arm, a latch pivotally connected thereto, a controller for said latch operatively connected to the replenishing mechanism, fixed means to cooperate the said controller, said means and controller having cooperating faces by means of which the controller is given a downward and forward movement subsequent to transfer. 110

3. In a weft replenishing loom, a transfer arm, a latch pivotally connected thereto, a controller for said latch normally in forward and downward position, means to raise the latch and controller to set the replenishing mechanism for transfer and to lower the controller during transfer, and means to give said controller a rearward movement as it is raised and a forward and downward motion to restore the same to normal position as the replenishing mechanism is reset. 120

4. In a weft replenishing mechanism, a transfer arm, a latch pivotally connected thereto, a controller for said latch, fixed means cooperating the said controller, said controller having cam portions to engage 125

the fixed means to cause said controller to have an initial rapid downward motion followed by a forward motion.

5. In a weft replenishing loom, a transfer arm, a transfer latch pivotally connected to the arm and having a slot therein, a latch controller operatively connected to the replenishing mechanism and having a portion thereof extending through the slot in the latch to restrain lateral displacement of said controller, said controller to lift the latch at the time of transfer.

6. In a replenishing loom having a lay with a bunter thereon, a transfer arm, a member pivotally connected to the transfer arm to engage the bunter on the lay, and a control member for said first named member,

one of said members being slotted to receive the other member to limit lateral displacement of said controller member. 20

7. In a weft replenishing loom a transfer arm, a latch pivotally connected thereto, a controller for said latch operatively connected to the replenishing mechanism, a guide for said controller, and means on the controller for giving the latter a forward and downward motion during replenishment, said latch engaging said controller to hold the latter in foremost position when the latch is in operative position. 25 20

In testimony whereof I have hereunto affixed my signature.

OSCAR W. RICHARDSON.
